H. O. AMES, OF NEW ORLEANS, LOUISIANA.

Letters Patent No. 61,650, dated January 29, 1867.

IMPROVEMENT IN ROTARY STEAM PUMPS.

The Schedule referred to in these Letters Patent and making part of the same.

TO ALL WHOM IT MAY CONCERN:

Be it known that I, H. O. AMES, of New Orleans, Orleans parish, and State of Louisiana, have invented a certain new and useful Improvement in Rotary Steam Pumps; and I do hereby declare that the following is a full, clear, and exact description thereof, which will enable others skilled in the art to make and use the same, reference being had to the accompanying drawings, forming part of this specification.

The present invention consists of a bucket-wheel arranged to revolve within a suitable casing, to which steam is admitted in any proper manner to act upon the buckets composing the wheel, and then exhausted or allowed to escape therefrom, in combination with a spiral screw-blade or shaft connected with and operated by the said bucket-wheel, which screw-blade is arranged to turn in the way or passage for the water, which, by its revolution, is thus drawn through such passage or way with a force and speed proportionate to that with which the bucket-wheel is revolved by the action of the steam and the gearing connecting it with the spiral screw-blade. In the accompanying plate of drawings, my improvements in rotary steam pumps are illustrated.

Figure 1 is an elevation of one side of the pump-casing, with portions broken out to show the interior construction and arrangement of the pump.

Figure 2, a transverse vertical section taken in the plane of the line xx , fig. 1.

Similar letters of reference indicate like parts.

A, in the drawings, represents a wheel, secured to a horizontal centre-shaft, B, arranged to turn in bearings of the sides C, of an upright casing or box, D, in which the said wheel turns steam-tight. This wheel, around its periphery, is provided with a series of buckets, E, at equal distances apart, to each of which, in regular order and succession, as the wheel revolves, steam is admitted through the steam passage F, communicating with the casing D at or near its top. The steam thus admitted acting upon the sides of the said buckets, revolves the wheel of which they form a part, and then escaping through the exhaust port G, at the lower portion of the casing D, enters the water-passage or way H. Around the periphery of the wheel A, to one side of its buckets, a gear-ring or wheel I is secured, with which interlocks or engages the toothed or gear-wheel J, arranged to turn, by its horizontal shaft K, in suitable bearings of the water-way or passage H, hereinbefore referred to. This gear-wheel J has openings L through it and upon each side of the same; a similar spiral or screw-shaped blade, M, is secured to and around its shaft K, the extreme diameter of which blade is equal or nearly so to the internal diameter of the water-way H. The shaft of the gear-wheel J is arranged so that it can be moved in its bearing to throw its gear into or out of gear with the bucket-wheel gear I, to accomplish which I use a lever-handle that is hung on a fulcrum in the water-way H, projecting outside of the same at one end, and at its other or forked or clutch end O, interlocking with an annular groove or recess, P, made in the spiral or screw-blade shaft K. From the above-described arrangement of the gear-wheel or screw-blade shaft K, and its connection with the lever-clutch O, it is plainly obvious that by moving the handle end of the said lever in the proper direction the gear-wheel J can be either thrown out of or brought into connection with the bucket-wheel gear, as the case may be; the said gear J, when in connection with the bucket-wheel, revolving in conjunction with it, and thus its screw-blades drawing and forcing the water through the water-way or passage H with a velocity and force in direct proportion to that with which the bucket-wheel is revolved by the action of the steam admitted to it and the intermediate gearing employed between it and the blade-shaft. In the use of my improved rotary-pump, a water pipe or hose suitable for conducting the water to and from the pump is first connected to the ends of the water-passage or way, when the screw-gear being thrown into connection with the bucket-wheel gear, by properly moving the lever-handle therefor, and steam being admitted to the bucket-wheel, the said wheel is revolved, and consequently the screw-blade shaft thereby drawing and forcing the water through the water-passage or way H with a force proportionate to the force exerted upon the bucket-wheel by the steam, and the arrangement of intermediate gearing, as hereinbefore stated, the steam escaping from the wheel-casing through the opening G, hereinbefore referred to, into the water-passage or way, where it condenses and mixes with the water passing through such way. By the arrangement and combination of the bucket-wheel and screw-blade shaft or propeller, for forcing the water through the water-passage, it is plainly apparent that more than one screw-blade shaft, each revolving in a suitable and separate water-way or tube, may be connected with one and the same bucket-wheel, thus increasing the effective power and working of the pump. In lieu of

arranging the revolving screw-blade outside of the bucket-wheel, it may be arranged so as to revolve in a position concentric therewith or at the centre of the bucket-wheel, the operation then being substantially the same, but this arrangement is not advisable when more than one water-way is to be employed or used in connection with one and the same bucket-wheel. I do not claim broadly the steam-wheel or the screw or propeller-blade by themselves or separately, as I am fully aware that they have both been separately used before, but

What I claim as new, and desire to secure by Letters Patent, is—

The steam-wheel A, and screw or propeller-blade M, combined together and arranged and operating substantially in the manner and for the purpose described.

The above specification of my invention signed by me this 29th day of June, 1866.

H. O. AMES.
